UNITED STATES PATENT OFFICE.

JAMES A. CASS, OF BROOKLYN, NEW YORK.

SPRINKLER-HEAD.

No. 899,904.

Specification of Letters Patent. Patented Sept. 22, 1908.

Application filed December 24, 1907. Serial No. 407,925.

To all whom it may concern:

Be it known that I, JAMES A. CASS, of Brooklyn, in the county of Kings, in the State of New York, have invented new and useful Improvements in Sprinkler-Heads, of which the following, taken in connection with the accompanying drawings, is a full, clear, and exact description.

This invention relates to certain improvements in sprinkler heads for automatic fire extinguishing systems and refers particularly to the general structure of the frame, strut, distributor plate and stopper mechanism.

One of the essential objects is to provide a spring frame which is tensioned by the adjustment of the strut so that when the integrity of the strut is broken by the burning of the fusible detent or detents, its resistance to the tension of the spring frame will allow the latter to retract and thereby more quickly and rapidly spread the parts of the strut to allow the opening of the stopper.

Another object is to provide the stopper with a non-corrosive insert or diaphragm forming the immediate cap or cover for the water opening through the sprinkler head so as to prevent any possibility of disintegration and consequent leakage and also to obviate any liability of the stopper sticking to its seat when released by the breaking of the strut.

Another object is to provide a sectional strut constructed in such manner as to relieve the fusible detents from severe strains when adjusted for use and at the same time to allow the parts of said strut to be readily separated and thrown out of operative position immediately upon the destruction of the detents by heat.

A further object is to provide a rotary distributing head with outwardly flaring radial channels forming the impact face for the discharging water when the stopper is released so as to deflect the water in sheets in all directions and at considerable distance from the center of the sprinkler head.

Other objects and uses will be brought out in the following description.

In the drawings—Figures 1 and 2 are respectively top plan and front elevation of a sprinkler head embodying the various features of my invention. Figs. 3 and 4 are sectional views taken respectively on lines 3—3 and 4—4, Fig. 2, except that the strut is shown in elevation in Fig. 3. Fig. 5 is an

enlarged longitudinal sectional view through the strut. Figs. 6, 7 and 8 are perspective views respectively of one of the end strut sections, the interposed tie plate or brace between the end strut sections and one of the detent plates. Fig. 9 is an inverted plan of the rotary distributing plate. Figs. 10, 11 and 12 are perspective views respectively of different parts of the stopper.

In carrying out the objects stated, I provide a spring frame comprising a tubular nipple —1—, and opposite outwardly arched spring arms —2— merging in a tubular hub —3— some distance from the nipple —1— forming substantially semi-circular bow arms rigidly secured at one end to the nipple —1— and preferably integral therewith and having their opposite ends free to yield toward and from said nipple. This nipple is formed with a central lengthwise water passage —4— therethrough and is also threaded exteriorly for securing to one of the pipe fixtures of the water discharging systems not shown.

The outer end of the nipple is substantially flat and forms a suitable seat for a lead washer or packing —5— upon which is mounted a cap —6— of German silver or other non-corrodible material which covers the outer end of the water passage —4—, said cap —6— being engaged by an outer disk —7— of brass or other suitable metal which is somewhat thicker and heavier than the cap —5— and gradually increases in thickness toward the center for increasing its strength and ability to resist the pressure of the strut, presently described.

The inner and outer faces of the disk —7— are preferably arched in opposite directions, the object of arching the inner face serving to make the disk self-centering and at the same time operating to depress the corresponding portion of the cap —6—, which is comparatively thin, into the adjacent end of the passage —4— thereby preventing the lateral displacement of the cap —6— and disk —7— when adjusted for use and at the same time more effectively bracing the inner edges of the packing —5— against its seat to avoid any possibility of leakage at this joint.

The packing —5—, cap —6— and disk —7— constitute a sectional stopper, the disk —7— being provided on its outer face with a central depression —8— for the reception and retention against lateral displacement of the adjacent end of the strut. This strut is

interposed midway between the spring arms —2— of the frame and is also interposed between the disk —7— and an adjusting screw —9— in the hub —3— and comprises two 5 opposite but similar interchangeable L-shape sections —10—, a tie piece —11— and brace plates —12— which latter are bound to the member —11— by interposed fusible detents —12'—, said member —11— being 10 similarly bound to the sections —10— by fusible detents —10'—.

The L-shape members —10— are arranged in an upright position with their bases at the opposite end of the strut and provided with 15 comparatively small tapering bosses —13—, one of which is seated in the recess —8— in the adjacent face of the disk —7— while the other boss is seated in a similar recess —14— in the inner end of the adjusting screw —9— 20 to hold the strut against lateral displacement relative to the disk —7— and screw —9—.

The inner faces of the bases of the L-shape members —10— are formed with grooves —15— constituting seats for the adjacent 25 ends of the tie piece —11— and fusible detent plates —12—. This tie piece —11— is formed with a central transverse rib —16— against the opposite face of which the adjacent ends of the detent plates —12— abut 30 while the opposite ends of said detent plates are seated in and abut against the bases of the grooves —15—, said detent plates and adjacent faces of the tie piece —11— being inclined outwardly or laterally and are located wholly at one side of the axis or center 35 line of the water passage and frame.

The opposite ends of the tie piece —11— terminate short of the basis of the groove —15— and the intervening space is filled in 40 with fusible material such as soft solder, similar fusible material being interposed between the adjacent faces of the tie piece —11— and detent plates —12— to normally lock or tie said detent plate to the tie plate 45 while the latter is secured by similar fusible material —17— to the adjacent faces of the strut sections —10—. The meeting ends of these strut sections —10— are slightly separated and the intervening space is filled in 50 with fusible material.

The grooves —15— and also the tie piece —11— and detent plates —12— are located wholly at one side of the axis of the frame or at one side of a straight line drawn between 55 the bosses —13— so that when the fusible material is destroyed by heat, the tension of the spring arms which is produced by adjusting the screw —9— against the strut operates to separate the parts of the strut and to 60 throw them out of position with a quick snap action.

The screw —9— is adjustable in a threaded aperture in the hub —3— and is provided at its outer end with a hand piece —20— 65 whereby it may be rotated, and upon the

outer end of this screw and outer face of the hub —3— is journaled a rotary distributor plate —21— having outwardly flaring wings —22— separated by intervening slots —23—, the wings —22— being provided on their outer 70 sides with outwardly and upwardly flaring recesses —24— and beveled faces —25— for the purpose of distributing the water radially in all directions in thin sheets some distance from the sprinkler head, the impact 75 of the water against the beveled faces —25— which are adjacent the slots —23— serving to rotate the head thereby lending centrifugal force to throw the water still farther from the sprinkler head and at the same time to 80 more evenly distribute it over the underlying surface or around the room in which the sprinkler head is located.

In operation, assuming that the strut and stopper are firmly adjusted by the screw —9— with sufficient force to slightly tension the spring arms —2—, then as soon as the fusible bond between the parts —10—, —11— and —12— is disintegrated by heat, said parts —10—, —11— and —12— tend to fall apart 90 and are positively forced out of operative connection with each other and with the stopper first by the relaxation of the tensioned spring arms —2—, and second by the pressure of the water against the stopper, this disintegration of the strut being facilitated by reason of the fact that the brace plates —12— are located wholly at one side of a direct line drawn between the bearings of the strut sections —10— at their points of engagement 100 with the disk —7— and screw —9—, it being understood that these plates —12— incline outwardly from said straight line and that they engage the sections —10— wholly at one side of the axis of the strut bearings so 105 that when end pressure is applied upon the sections —10—, it tends to tilt the meeting ends of said sections in the direction of the brace plates —12—, this action being instantaneous upon the disintegration of the 110 fusible bond and therefore, the strut sections are displaced or thrown forcibly to the side of the axis at which the brace plates —12— are located.

What I claim is:

1. In a sprinkler head, a stopper, and means for holding said stopper in place including a strut consisting of L-shape sections arranged end to end, braces engaging the bases of the strut sections, a tie piece between the braces and strut section, and fusible material uniting the braces to the tie piece.

2. In a sprinkler head, a strut consisting of L-shape sections arranged end to end with their bases at the extreme end of the strut and provided with pointed bearings, a tie piece extending across the meeting ends of the L-shape sections and provided with a rib on its outer face, outwardly inclined 130

braces arranged one above the other and having their meeting ends engaged with said rib and their opposite ends engaging the bases of the L-shape sections, and a fusible bond uniting the tie piece to the L-shape sections and to said brace plates.

3. In a sprinkler head, a strut consisting of L-shape sections arranged end to end with their bases at the extreme end of the strut and provided with pointed bearings, a tie piece extending across the meeting ends of said L-shape sections, a fusible bond between the tie piece and said L-shape sections, brace plates lying wholly at one side of the axis of the strut and engaging the bases of said L-

shape sections, and a fusible bond between the braces and tie piece.

4. In a sprinkler head, a tubular nipple, a German silver disk covering the discharge end of the nipple, a brass disk resting against the German silver disk, and means including a tensioning screw for holding the disks in place.

In witness whereof I have hereunto set my hand this 16th day of December 1907. 25

JAMES A. CASS.
